COMBINED RADIO, PHONOGRAPH AND TELEVISION CONSOLE

Daniel J. Domin, Deerfield, and Thomas E. Duvall, Morton Grove, Ill., assignors to TMA Company, Wheeling, Ill.

Filed Dec. 24, 1969, Ser. No. 20,625

Term of patent 14 years

Int. Cl. D14—03

U.S. Cl. D56—4

FIG. 1 is a front and right side perspective view of a combined radio, phonograph and television console, showing our new design with the cover in raised position;

FIG. 2 is a front elevational view with the cover closed; and

FIG. 3 is a top and front perspective view thereof.

The rear and bottom, not shown, are substantially flat and unornamented surfaces.

We claim:

The ornamental design for a combined radio, phonograph and television console, substantially as shown and described.
